WILLIAM B. ARNOLD, OF NORTH ABINGTON, MASSACHUSETTS.

PROCESS OF FORMING WELTING.

1,122,845.

Specification of Letters Patent.

Patented Dec. 29, 1914.

Application filed April 20, 1912 Serial No. 692,024.

To all whom it may concern:

Be it known that I, WILLIAM B. ARNOLD, a citizen of the United States, and a resident of North Abington, in the county of Plymouth and State of Massachusetts, have invented an Improvement in Processes of Forming Welting, of which the following description, in connection with the accompanying drawings, is a specification, like characters on the drawings representing like parts.

This invention relates to the process of forming welting for boots and shoes.

In order that the principle of the invention may be readily understood, I shall set forth the steps constituting the process and the best mode known to me for carrying the process into effect.

In the accompanying drawings, I have shown one form of welt produced by my process, and have therein indicated the steps involved in applying the same to the boot or shoe and in finishing the welt when so applied.

Referring more particularly to the drawings, Figure 1 is a cross section taken through a shoe having applied thereto a welt constructed in accordance with my invention, and representing the condition of the out-sole prior to the rough rounding operation; Fig. 2 is a view similar to Fig. 1, but representing the condition of the out-sole after rough rounding operation; Fig. 3 is a cross sectional detail on an enlarged scale showing more clearly the method of securing the welt in position; Fig. 4 is a plan view of a welt produced in accordance with my invention and looking at the grain face thereof; Fig. 5 is a cross sectional view upon an enlarged scale of the welt shown in Fig. 4. Fig. 6 is a diagrammatic view illustrating the method of cutting the welt from a leather sheet or blank in accordance with my invention; and Fig. 7 is a view similar to Fig. 6, but indicating the former manner of cutting welting.

The high cost of leather renders necessary the saving of all possible material. It is therefore highly desirable that the welts of boots and shoes be cut with the least possible waste. Welts are usually cut as strips of indeterminate length from a blank by cuts which are normal to the faces of the blank, so that the welt is rectangular in cross section when cut from the blank. In order that the welt may be properly applied

to the boot or shoe, it is desirable that its inner edge be of reduced thickness or tapered. This taper is usually given to the welt after the welt has been cut from the blank, though in some cases a strip wide enough for two welts is cut from a blank as shown, for example, in Fig. 6, in the patent to Bicknell, No. 707,076, and in Figs. 3 and 6 of the patent to Hadaway, No. 744,752, said strip being cut into two welts by a cut inclined to the faces of the strip as there indicated. While cutting a strip into two welts in the manner indicated in said patent affords a certain saving of material, it is the purpose of my invention to effect an increased saving.

Welts vary in width but are customarily from one half to three quarters of an inch in width. Assuming the normal welt to be one half inch in width, I am enabled in the practice of my invention to save substantially from one-eighth of an inch to one-quarter of an inch upon the width of two welts or from one-sixteenth to one-eighth of an inch to every welt, depending upon the inclination of the bevels thereof. That is to say, I am enabled to save one-eighth or one-quarter of all the material, thereby permitting the production of an increased number of welts from a blank of given size.

Assuming that the extreme width of a welt is to be one-half inch, and assuming that each welt should have a tapered inner edge to permit it to be secured in more effective manner to the shoe, instead of cutting the leather blank into strips, each rectangular in cross section and one-half inch along each face, as indicated in Fig. 7, I cut the blank into strips by cuts, all of which are parallel to each other and are separated about six or seven-sixteenths of an inch from each other as indicated in Fig. 6, depending upon the angle of the tapered cut. It will be apparent that the full width of the welt is one-half inch and that the inclined cut at the outer edge of each welt furnishes the desired inclined edge of the next welt. Therefore, I effect a great saving over that manner of cutting a welt which consists in cutting it into strips rectangular in cross section and thereupon beveling the inner edge and I also effect a very substantial saving over that method of cutting the welt above referred to which consists in first cutting a strip of the width of two welts and then separating them by

an inclined cut. The amount of saving effected by my invention over such manner of cutting the welt last referred to amounts to the full width of the tapered portion of the welt. Moreover I save a step in the manufacture of the welt because heretofore it has been customary to cut the welt into a rectangular form in cross section and then to bevel the inner edge and channel the flesh face. I am enabled to dispense with said beveling as a separate operation because such beveling is inherent in the separation of the stock into welts.

The direction of bevel in the welt formed in accordance with my method is preferably and is here shown as such that the upper or grain face thereof at its outer edge when applied to the shoe, terminates short of the lower or opposite face of the welt, though within the scope of my invention the direction of bevel may be such that the upper or grain face, when applied to the shoe, extends outwardly beyond the lower face of the welt. In beveling the welt in accordance with my invention, I secure certain important advantages. In the first place, I secure an important saving of material at the outer edge of the welt, since the material removed in the final trimming operations from the outer edge of the welt is not or need not be more than the amount of the bevel itself, and at certain parts at least of the shoe, as for example at the outer ball portion thereof, a portion or all of the outer bevel may be left in the final trimming operation. Inasmuch as the welt, when applied to the shoe, is provided with an outer edge of reduced thickness, the welt is less rigid than one having an outer edge at right angles to its faces. By reason of the described beveling of the outer edge of the welt, the latter is rendered more pliable and can be applied far more readily to the shoe and particularly can it be bent around the toe thereof. In other words, not only is the beveling of the outer edge of the welt advantageous in that thereby I provide a beveled inner edge of the adjoining welt in the act of cutting the welt from the stock or leather sheet, but a welt having a beveled outer edge is structurally advantageous, owing to the fact that it can be thereby more readily and accurately applied to the shoe. Obviously when the welt has been applied to the shoe, its beveled outer edge has completely subserved its function of rendering the welt more pliable and its subsequent removal is immaterial, though as above indicated I may and preferably do retain a portion thereof in the completed shoe, depending upon the style or type of shoe.

Referring more particularly to the drawing, one form of welt produced in accordance with my invention is represented at 1 in the several figures, the grain face thereof

being indicated at 2 and the flesh face at 3. The welt may be and preferably is provided upon its flesh face with a stitch anchoring shoulder which may be provided by channelling the welt adjacent its inner edge, as indicated at 4 in Fig. 5 or by applying a strand or line of stitching or the like.

As shown in Figs. 5 and 6, the edges of the welt are tapered in substantial parallelism, as indicated at 5 and 6, each welt when cut presenting an obtuse angle at the grain face at its outer edge and an acute angle at the grain face at its inner edge. The cuts by which the blank is separated into welts are preferably straight as herein indicated.

The welt 1 is secured to the insole 8 as shown in Fig. 1 by a line of through and through stitching 9 passing through the insole, the welt and the upper 10. It is evident that if the taper or bevel of the inner edge be very gradual, the stitches 9 passing through the welt from the stitch anchoring shoulder 4 will issue from the welt at some point in the tapering portion of the inner edge instead of emerging through the grain face thereof. It is desirable that the stitches emerge through the grain face itself, as thereby a greater amount of stock is penetrated by the stitching which will therefore be held more effectively and the grain face itself affords greater resistance than the other portions of the leather. In order therefore to make certain that the line of stitching will emerge through the grain face itself or substantially along the line of junction of the grain face and the taper of the inner edge, I preferably incline the cuts by which the blank is severed into welts at such an angle as to provide substantially blunt tapers, as indicated in the several figures. In this manner the grain face of the welt will, when the welt is applied to the shoe, extend sufficiently inward to receive the stitching and thereby effectively support the welt as described. After the welt has been secured to the shoe and the out-sole applied thereto, as indicated in Fig. 1, the welt and out-sole may be trimmed in the usual manner.

The outer edge of a square-edged welt and the outer edge of the sole are invariably trimmed in finishing the shoe, and the portion of the square edged welt thus cut off would always equal in width at least the width or extent of the bevel or tapered outer edge and would be of at least double the mass, unless an extreme taper or bevel be resorted to. Therefore there is no loss incurred in trimming off the outer beveled edge after the welt has been applied, beyond that always inherent in the finishing of boots and shoes, and as already stated, a portion at least of the outer beveled edge may be left uncut in the finishing operation.

It will be evident from the illustration and from the foregoing description that by employing a welt having an inner beveled edge, such as 5, which is to be applied to the outer surface of the upper 10, by reason of such beveled surface, the welt may be maintained substantially flat when and after it is being sewed to the insole and to the upper; that is, the beveling of the inner edge 10 permits the welt so to be applied to the outer surface of the upper that the stitching may be applied thereto, as illustrated in Fig. 5, without bending or deflecting the welt, as is the case when the inner edge of the welt is 15 at right angles to the upper and lower face thereof. Aside, therefore, from the saving in material heretofore referred to, by my invention I am enabled so to prepare the welt for application to the shoe that it may 20 be more readily secured thereto.

The beveling of the inner edge of the welt; that is, that edge of the welt that is applied to the upper,—so prepares the welt that when applied to the shoe, it is not only 25 more elastic but it is necessary to cut off far less material between the line of stitching and the body of the shoe than in those welts which are rectangular in cross section. In fact, it is unnecessary to remove 30 any substantial amount of such inner edge. In other words, the welt produced in accordance with my invention is not only of great commercial value, because of the very substantial saving in stock resulting therefrom, 35 but the cutting of the welt in the manner described prepares the same for application to the shoe, and it fits thereto more easily and elastically than does the rectangularly shaped welt, and furthermore less subsequent treatment of the inner edge of my welt 40 is required than in those of rectangular shape.

It will be apparent from the foregoing description that by cutting the welt as above 45 described I effect a very substantial saving of material, such saving of material being represented by every ninth welt or more cut from the blank.

The welt produced in accordance with my 50 invention, when applied to the shoe and finished in the trimming operations, is fully as wide as a welt having square edges but having each face of the same width as the corresponding face in the welt herein disclosed. In other words, a square edged welt 55 such as described, after being applied to the shoe and trimmed in the finishing operations, is no wider than a welt produced in accordance with my invention when applied 60 and similarly trimmed.

Welt users and shoe manufacturers classify welts according to their extreme widths, and inasmuch as the extreme width of a welt constructed in accordance with my invention 65 exceeds the extreme width of a square edged

welt, each face whereof is of the same width as the corresponding face of a welt constructed in accordance with my invention, it will be evident that the latter is classed as a wider welt than the square edged welt referred to. 70

After any welt has been sewed to the shoe, the rough rounder cuts off the edge of the sole and of the welt. The amount of welt taken off at the different points about the shoe varies, the least width being usually taken off at the outside ball portion of the foot. At substantially any point, however, excepting the outside ball portion, the width of welt cut off by the rough rounder is one 75 sixteenth of an inch or more, and in Fig. 1 I have represented the outsole 11 as it appears or may appear before it has been trimmed in the rough rounding operation. This is invariably cut off. The welt is 80 never left uncut, but is always trimmed by the rough rounder, not only to give the approximate desired shape, but to secure clean stock about the entire shoe. That is to say, it is the invariable practice to trim the welt 85 at all points, not only to give the required shape, but also to produce a fresh cut edge. In addition to the width of welt cut off by the rough rounder, the trimming machine cuts off an additional amount varying from 90 one sixty-fourth to one thirty-second of an inch. Therefore, no welt in the finished shoe is of that full width possessed by the welt when first sewed in place and before it is trimmed by the rough rounder. Depend- 95 ing upon the type and style of shoe, the rough rounder may remove a portion or substantially all of the outer bevel at parts of the shoe, though in Fig. 2 I have represented the said beveled edge as left intact 100 at one side of the shoe (the outer ball portion) and as partially removed at the opposite side. 105

The sole of a shoe as applied thereto and before it is trimmed is never absolutely 110 square at the edge. It is substantially impossible to die out a sole so that its edges will be absolutely square, though attempts have been made to produce this result by somewhat inclining or beveling the dieing 115 out edges to compensate for the irregularity or taper always produced in attempting to cut the sole absolutely square. Therefore, it is always necessary that the sole be trimmed along its edges to secure a square edge. This 120 trimming of the edge of the sole is accompanied by a trimming of the edge of the welt, so that the width of the final welt is always less than the distance between the face of the upper and extreme outer edge of 125 the welt when sewed to the shoe, but prior to the rough rounding operation. It will therefore be evident that a welt originally square edged must be invariably and very materially trimmed at its outer edge, so that 130

it is never ultimately of its full primary width. The amount that must be trimmed off the outer edge of a square edge welt is always at least equal to the amount of the 5 bevel in the welt constituting my invention. It can never be less than the amount of said bevel.

From the foregoing, it will be evident that a welt constructed in accordance with my 10 invention and originally having a beveled outer edge is not narrower in the finished shoe than a welt originally having a square outer edge and having faces of the same width as the faces of applicant's welt, but 15 on the contrary is of the same width in the finished shoe as said square edged welt; that is, the width from the shoe upper to the outer edge of the welt is the same in both cases.

20 The trimming machine usually employed for the purpose of trimming the welt and sole is provided with a rotating cutter composed of a hub having a series of inclined blades extending in a general radial direction 25 therefrom. Each of said blades is provided at its outer end with a cutting edge, the central or main portion of which is vertical and the upper, and sometimes the lower portion, of which are inclined so as to provide 30 projecting cutting shoulders triangular in vertical section at the upper and lower faces of each blade. The said cutting shoulder at the upper edge is customarily provided for the purpose of beveling off the 35 upper, outer edge of the welt to give a finished appearance thereto.

The welt herein disclosed, provided as it is with a beveled, upper, outer edge, is 40 trimmed with the sole by the rough rounder into approximate shape, the amount of material taken off varying to suit the style or 45 type of shoe. Depending upon the style or type of the shoe, more or less of the beveled, upper, outer edge is left untouched or intact by the rough rounder, and this is particularly the case at the outer, ball portion of the shoe, which is customarily left of the full 50 width of the welt. Therefore, when the shoe is removed from the rough rounder, a considerable portion of the welt, depending in extent upon the character of the shoe, has its upper, outer edge beveled. This bevel constitutes a support and guide for the upper shouldered portion of the trimming machine cutter, previously described, and not only facilitates the proper application of the welt and sole to the said cutter but constitutes a starting point for the cutting operation, as-

suming such bevel to have been left only at the outer, ball portion of the shoe. In other words, not only is the welt rendered more pliable or flexible, because of the outer beveled edge thereof, thus permitting said welt to be more readily flexed about or applied to the shoe, but the said bevel constitutes a 60 guide or support in the finishing operation. Further, it is evident from the foregoing that it is unnecessary, when the outer bevel extends in the direction herein indicated, to remove in the finishing operation a portion 65 of the width of the welt equaling the full extent of the taper, as a substantial portion of said taper may be retained to constitute a finishing shoulder. Moreover, the bevel, when at the upper, outer edge of the 70 welt, as herein disclosed, constitutes an indicating mark, particularly at the outer ball 75 portion of the foot, by which the operative is guided in his work. In other words, knowing that it is desirable to leave the said bevel or shoulder at the outer ball portion of the foot, he so guides the shoe as to effect this result, whereas if the welt has an outer, 80 upper square edge with no mark inside of such outer edge to which he must not cut, 85 then he is more apt to cut too far in. In the welt herein described, the inner, upper edge of the welt lying as it does at a substantial distance inside the outer edge of the sole, 90 constitutes a safety mark, as it were, outside of which the cutting should be carried on.

Having thus described one illustrative embodiment of my invention, I desire it to be understood that although specific terms are 95 employed, they are used in a generic and descriptive sense and not for purposes of limitation, the scope of the invention being set forth in the following claim.

Claim:

That process of forming welting in indeterminate lengths which consists in cutting a leather strip by a series of straight, parallel cuts, inclined in the same direction to the faces of the sheet, into welt strips, and 105 providing one face of each strip with a stitch anchoring shoulder adjacent one of its edges.

In testimony whereof, I have signed my name to this specification, in the presence 110 of two subscribing witnesses.

WILLIAM B. ARNOLD.
